Fred D. Ackley INVENTOR.

BY

A. P. Gwin

ATTORNEY.

UNITED STATES PATENT OFFICE.

FRED D. ACKLEY, OF KIRKLAND, WASHINGTON.

CARBURETOR.

Application filed October 14, 1920. Serial No. 416,909.

To all whom it may concern:

Be it known that I, FRED D. ACKLEY, a citizen of the United States, and residing at Kirkland, in the county of King and State 5 of Washington, have invented certain new and useful Improvements in Carburetors, of which the following is a specification.

This invention relates to an attachment 10 for carburetors wherein substantially all liquid fuel may be separated from the atomized fuel in accordance with and proportional to the speed of the engine.

With the engine idling or running at low speeds, it is desirable that practically all of 15 the liquid fuel be separated from the gas stream and only the atomized fuel be permitted to enter the engine, while as the speed increases, in order that a proper fuel supply may be had, it is desirable that a correspondingly increased proportion of the fuel be 20 permitted to enter the engine, in order that the increased demand for fuel will be met.

The present invention is designed to automatically take care of this condition, so 25 that at low speeds practically all of the liquid fuel is separated from the gas stream and at increased speeds a corresponding increased proportion of fuel is held against separation from the gas stream and caused 30 to enter the engine.

In the drawings:—

Fig. 1 is a vertical section view partly in elevation illustrating the application of the attachment.

Fig. 2 is a section on line 2—2 of Fig. 1.

Fig. 3 is an end view of the improved device.

Fig. 4 is a plan showing the operating means for the attachment.

The improved device is arranged in the 40 intake manifold and forms a part thereof. The device comprises a chamber 1 concentric with and of greater diameter than that of the manifold 2. The device includes a 45 tubular extension 3 opening from the chamber 1 and corresponding to the manifold in diameter, the free end 4 of the extension, and the corresponding opening 5 from the opposite end of the chamber being formed 50 with appropriate plate sections 6, whereby the device may be connected by bolts or the like to the carburetor outlet 7 and to the manifold 2. The extension 3 of the device is thus in line between the carburetor and manifold, while the chamber 1 forms a receptacle of increased area concentric with the

manifold. Connecting the extension 3 and the outlet opening 5 of the chamber is a sleeve-like member 8 having a diameter corresponding to that of the extension and divided longitudinally by narrow ribs 9 to thus form a series of openings 10 in such sleeve member. The openings 10 thus constitute a greater portion of the area of the sleeve member and extend a portion of the 60 length only of such member, as clearly shown in Fig. 2. A sleeve cut-off 11 slidably embracing the member 8 is mounted thereon, the cut-off being of such length that when in inoperative position, as shown in 65 Fig. 1, the interior of the sleeve member 8 is opened to the chamber 1 through the openings 10, while when the cut-off is drawn toward the carburetor, the size of the openings 10 is correspondingly reduced, until in 70 a fully operative position, the interior of the sleeve member is wholly closed against the chamber. Integral with and to one side of the extension 3 is a cylindrical body 12 in which is rotatably supported a rod 13. A 75 pin 14 extends laterally from the rod 13 to within the extension 3, and said pin is connected at its end with the cut-off 11 through divergent rigid connectors 15. The upper end of the rod 13 is provided with 80 a lateral arm 16 having an operating bar 17 pivotally connected to the free end thereof. The end of the bar 17 remote from the arm 16 is formed with a slot 18 to receive a 85 pin 19 depending from the arm 20 connected to and arranged to control the usual butterfly valve 21. A spring 22 is connected to one end of the arm 16 and to a pin 23 on the carburetor or other appropriate part, the spring being normally tensioned to so operate 90 the rod 13 as to move the cut-off into open or inoperative position.

It will be apparent that with butterfly valve substantially closed, as when the engine is operating at low speed, the cut-off 100 11 will be in inoperative position, that is the position shown in Fig. 1, in which position practically all of the liquid content of the fuel will gravitate from the gas stream into the chamber 1, from which it may be 105 delivered through an outlet 24 to the bowl of the carburetor or other storage chamber. As the throttle valve is opened to increase the speed of the engine, the arm 20 by which the butterfly valve is controlled, will be permitted 110 to move an appreciable distance, through the pin and slot connection 18 and

19 before effecting corresponding movement of the arm 17. At the predetermined point however, the arm 17 will be operated drawing upon the cut-off to gradually close the 5 openings 10. When the engine reaches a predetermined speed, which of course may be regulated by proper proportions of the parts, the cut-off will prevent any escape of the liquid fuel in the gas stream, and 10 will compel all such fuel to enter the engine as is desirable.

Claims:—

1. A carburetor attachment comprising a liquid fuel chamber, a sleeve having openings communicating with said chamber, said sleeve being connected in line with the intake manifold from the carburetor, and means governed in the control of the fuel passing through the intake manifold to vary 15 the size of said openings.
2. A carburetor attachment comprising a fuel conduit forming part of an intake manifold and having outlet openings therein, a chamber surrounding said conduit to receive 20 fuel delivered through said openings, a cut-off slidable on the conduit to control said openings, and means operated in the control of the fuel passing through the intake manifold to actuate said cut-off.
3. A carburetor attachment comprising a fuel conduit forming part of an intake manifold and having outlet openings therein, a chamber surrounding said conduit to receive 25 fuel delivered through said openings, a cut-off slidable on the conduit to control said openings, and means operated in the control of the fuel passing through the intake manifold to actuate said cut-off, said means having a limited movement without effecting 30 the cut-off.
4. A carburetor attachment comprising a casing having openings in the ends thereof, a tube formed with cut-away portions mounted in the openings, a sleeve valve slid- 35 ably mounted on the tube between the ends of the casing, one of the ends formed with

a neck, a bearing transversely integral with said neck portion adapted to receive a pintle, a bell crank integral with said pintle, a lever pivotally mounted to said bell crank, 50 said lever yieldingly attached to a carburetor control means.

5. A carburetor attachment comprising a casing, centrally disposed aligned openings therein, a tube mounted in the casing formed with cut-away portions, a sleeve valve slidably mounted on said tube between the ends of the casing, one of the ends formed with a neck, a bearing transversely integral with 55 said neck portion adapted to receive a pintle, a bell crank integral with said pintle, a lever pivotally mounted to said bell crank, said lever yieldingly attached to a carburetor control means, a pin rigidly mounted in the said pintle whose outer end is formed 60 with a recess, a yoke means pivotally mounted in the recess of said pin the ends of said yoke being pivotally connected to the said sleeve, said pin adapted to move the said sleeve in one direction, means for 65 attaching the said casing in between a manifold and carburetor, a control means for the said carburetor adapted to move the said sleeve at a predetermined time, a pipe communicating with the interior of the casing 70 and integral therewith, for conveying the liquid contents of the casing away from the casing.

6. A carburetor attachment comprising a casing having centrally disposed and aligned 75 openings therein, a tube mounted in the casing and formed with cut-away portions, a sleeve valve slidably mounted on said tube, one of the end plates of said casing formed with a neck portion, a bearing transversely 80 integral with the said neck portion, a pintle revolvably mounted in said bearing, a bell crank integral with said pintle, means for returning said pintle to a normal position, 85 said means being a spring.

In testimony whereof I affix my signature.
FRED D. ACKLEY.
